Primary Examiner — Eric Goodman*Assistant Examiner* — Daniel J Domino*(74) Attorney, Agent, or Firm* — Beth L. McMahon(57) **CLAIM**

The ornamental design for a display screen or portion thereof with graphical user interface, substantially as shown and described.

DESCRIPTION

The FIGURE is a front view of a display screen or portion thereof with a graphical user interface.

The use of the color black represents contrast only and not the claimed color.

The outer broken line perimeter of a display screen or portion thereof, as well as the words, numbers, symbols, and portions of the graphical user interface illustrate portions of the article, and form no part of the claimed design.
